LE ROY KRAMER
SPRING RETAINER FOR SPRING CUSHION CONSTRUCTIONS AND METHOD
OF PRODUCING THE SAME
Filed Oct. 2, 1924

UNITED STATES PATENT OFFICE.

LE ROY KRAMER, OF CHICAGO, ILLINOIS, ASSIGNOR TO CONTINENTAL CUSHION SPRING COMPANY, OF CHICAGO, ILLINOIS, A CORPORATION OF ILLINOIS.

SPRING RETAINER FOR SPRING-CUSHION CONSTRUCTIONS AND METHOD OF PRODUCING THE SAME.

Application filed October 2, 1924. Serial No. 741,215.

This invention relates to spring retainers for spring cushion constructions and method of producing the same, and among its principal objects are economy in production,

5 simplicity in construction, and the saving of labor and time in their production. An important factor in the production of spring retainers of the character described herein is cost of production, another is time. The 10 reduction of one or both is of great importance, where competition is keen and profits low. In the construction of most all, if not all, spring retainers for spring cushions, the work of sewing together the parts which 15 comprise the spring retainers, is done by comparatively cheap labor, but in order to produce in large quantities, a great many operators are required. It is my aim to provide a spring retainer and a method for 20 producing the same which will enable me to dispense with large numbers of operators, and at the same time increase the output and reduce the cost of production.

With these and other objects and advantages in view, this invention consists in the several novel features hereinafter fully set forth and claimed.

The invention is clearly illustrated in the accompanying drawing, in which:

30 Fig. 1 is a perspective view of a spring cushion construction, partly assembled and partly broken away, one of the spring retainers, embodying the present invention, being shown in position ready for insertion into the structure; Fig. 2 is a perspective view of a fragment of one of the spring retainers, and showing one step in the method of constructing them, and Fig. 3 is a plan of a strip of material from which a spring 35 container or cell structure is constructed.

40 Referring to said drawing, which illustrates one embodiment of the present invention, the reference character 5 designates a multiple compartment, spring container of suitable dimensions to form the complete 45 spring cushion construction. In accordance with the usual practice it may be formed of a top 6, bottom 7, spaced parallel partitions 8 and end walls 9, all formed of suitable textile fabric sewn, stapled, stitched or secured together in any desirable manner.

The spaces between the partitions form elongated compartments for receiving the spring retainers and the coiled springs, as usual.

55 The spring retainers 10 comprise top and bottom members 11, 12 with spaced, parallel, transverse partitions 13 and end walls 14 extending therebetween and connected thereto. The top, bottom and transverse 60 walls form cells or compartments, each of which is adapted to receive a coiled compression spring (not shown) or other elastic element, and one spring retainer with the 65 springs contained in the cells thereof is placed in a compartment of the multiple compartment spring container 5.

The spring retainer forming the subject matter of this specification, is constructed of short strips of fabric A, (see Fig. 3), 70 each of sufficient length to form the top a, bottom a¹, and partition a², of one cell structure, with enough additional material to overlap and be secured to the top and bottom of an adjacent cell structure. The edge 75 portions a³ of the top and bottom of each cell structure overlap the partition wall a² of an adjacent cell structure and are secured to the top and bottom walls of said adjacent cell structure by stitching, sewing or stapping them thereto and for convenience I have shown the cell structure secured together by staples 15 that are driven through the material, as shown and clinched down upon it.

80 85 The short strips A, may be cut from a continuous length of fabric, assembled with other strips and secured thereto by automatic machinery, to form spring retainers containing any number of cells and any size. 90 The structure may be made in a continuous length, if desired, and may be cut into suitable lengths. If desired, a separate end wall as shown at a⁴ may be provided at one end of an end cell structure, in order to 95 avoid any waste of material.

In constructing a spring retainer in accordance with the present method, the short cell structure strips A, are first cut from a continuous length strip of fabric, each strip 100 is then folded or formed up into a channel shape cell structure, roughly speaking; each

channel shape piece is then partly nested over an adjacent one and the edge portions of one channel shape cell structure is then stitched, stapled, sewed or otherwise fastened 5 to said adjacent one at or near the partition wall a^2 .

The spring retainers may be made in a continuous length and thereafter cut into any desired length, or may be built up originally 10 into desired lengths by suitable automatic machinery, no claim being made herein, to any such machinery.

It is to be understood that the textile strips, when arranged in succession, with 15 their ends secured along two spaced parallel lines, to an adjacent strip, assume the channel like form mentioned, when the entire structure is stretched out into full length. The parts a , and a^1 thereupon form the top 20 and bottom members of the spring retainer and the parts a^2 form the transverse partitions.

More or less variation of the exact details 25 of construction is possible without departing from the spirit of this invention; I desire, therefore, not to limit myself to the exact form of the construction shown and described, but intend, in the following claims, to point out all of the invention disclosed herein.

I claim as new, and desire to secure by Letters Patent:

1. A spring retainer for spring cushion constructions, comprising a plurality of 30 channel shape, textile cell structures, each formed of a continuous strip of material, and all successively arranged, with the end edge portions of each cell structure secured to an adjacent cell structure at two spaced 35 places thereon.

2. A spring retainer for spring cushion 40 constructions, comprising a plurality of channel shape, textile cell structures, each formed of a continuous strip of material, and all successively arranged with their end 45 edge portions overlapping and secured to

an adjacent cell structure at two spaced places thereon.

3. A spring retainer for spring cushion 50 constructions, comprising a plurality of channel shape, textile cell structures, each formed of a continuous strip of material, and all successively arranged with the end edge portions of each cell structure stapled to an adjacent cell structure along two spaced lines intermediate the ends of said adjacent cell structure.

4. A spring retainer for spring cushion 55 constructions, comprising, successively arranged strips of textile material, the end edge portions of each strip being secured, along two spaced lines, to an adjacent strip, and forming therewith a cell structure.

5. A spring retainer for spring cushion 60 constructions, comprising successively arranged strips of textile material, the end edge portions of each being stapled, along two spaced, parallel lines, to an adjacent strip, and forming therewith a cell structure, adapted to receive a spring.

6. A spring retainer for spring cushion 65 constructions, comprising a plurality of three sided, textile cell structures, successively arranged and secured together, the three sides of each cell structure and one side of 70 an adjacent one forming a four sided cell.

7. The herein-described method of producing 75 spring retainers for spring cushion constructions, which consists in successively securing the end edge portions of textile strips 80 of material to other textile strips of material, along two spaced lines, intermediate the ends of said other strips.

8. The herein-described method of producing 85 spring retainers for spring cushion constructions, which consists in successively stapling the end edge portions of textile strips of material to other textile strips of material, along two spaced lines, intermediate the ends of said other strips.

LE ROY KRAMER.
